(57) CLAIM

The ornamental design for a cushion, as shown and described.

DESCRIPTION

FIG. 1 is a bottom, front and right side perspective view of a cushion, showing our new design;

FIG. 2 is a top, rear and left side perspective view thereof; FIG. 3 is a bottom, rear and left side perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is an enlarged view of the portion labeled “10” in FIG. 3; and,

FIG. 11 is an enlarged view of the portion labeled “11” in FIG. 3.

The dot-dash broken line rectangle frames define the boundary of an enlarged view and form no part of the claimed design.

1 Claim, 11 Drawing Sheets
